UNITED STATES PATENT OFFICE.

JOSEPH GEDDES, OF ROCHESTER, NEW YORK.

CAR-COUPING.

SPECIFICATION forming part of Letters Patent No. 268,789, dated December 12, 1882.

Application filed October 27, 1882. (No model.)

To all whom it may concern:

Be it known that I, JOSEPH GEDDES, of Rochester, Monroe county, New York, have invented a certain new and useful Improvement in Car- 5 Couplings; and I do hereby declare that the following is a full, clear, and exact description of the same, reference being had to the accompanying drawings, in which—

Figure 1 is a longitudinal vertical section in line *xx* of Fig. 2. Fig. 2 is a plan with the top removed. Fig. 3 is an end elevation of one of the draw-heads on an enlarged scale, showing the spring arrangement for turning the shackles. Fig. 4 is a plan showing the chain for disengaging the spring. Figs. 5 and 6 are detail views.

My improvement relates to car-couplings in which two shackles are used, provided with barbed heads which engage with catches in the draw-heads.

20 The invention consists in the construction and arrangement of parts hereinafter described and claimed.

In the drawings, *A A* represent the two draw-heads of two meeting cars. These draw-heads 25 differ from ordinary draw-heads in being made very short and having no shank running back under the car, as in the common arrangement.

30 *B B* are loops or stirrups bolted to the bottom of the car. The draw-heads rest loosely in these loops, so as to have a limited movement forward and back therein. On the back of each draw-head is a projecting lug, *D*, having a slot, *a*, in its top.

E is a firm stud, projecting downward from 35 the bottom of the car and resting in the slot.

b b are two stiff spiral springs, resting in the slot *a*, and on opposite sides of the stud. When the cars are under motion the strain comes 40 upon the stud *E* and against one or the other of the springs *b b*, and by this means also the necessary elasticity is obtained to break the shock in either direction. The draw-head is retained in place by the loop or stirrup *B*, before described. By this means the long shank 45 or bar of the draw-head ordinarily used is avoided, which simplifies the device and reduces the expense.

50 *F F* are the two shackles, one attached to each draw-head. Each consists of a straight rod or bar of iron having a flat double-barbed

head, *c*, at one end, the other end passing through a slot, *d*, in the back of the draw-head to which it is attached, projecting outside, and provided with a coiled spring, *f*, which has a tendency to draw it backward.

55 *g* is a square shoulder formed in the bottom of the interior of the draw-head and just back of its mouth.

h is a swinging catch, hung in the draw-head above the shoulder *g*, leaving just space enough 60 between to allow the barb of the shackle to pass outward in uncoupling when the barb is turned flatwise. The catch, when in a vertical position, is prevented from opening forward by a stop which it strikes; but it is allowed to 65 swing backward in coupling, as will be herein-after described.

65 *G* is a flat spring, attached to the side of the draw-head.

70 *H* is a lever attached to the shackle, thence extending upward, and connected with the top of the spring by a jointed link, *k*. In the two draw-heads the spring attachments are on opposite sides.

75 *I* is a chain attached to each draw-head on the same side where the spring is located, and provided with a pin, *l*, which passes through a hole, *m*, in the front of the opposite draw-head, for the purpose of securing the lever, as will 80 be presently described.

85 In their natural position the shackles stand with their barbs vertical, so that when the cars are brought together the barbs will ride up over the shoulder *g* and fall behind, one side engaging with the shoulder *g* and the other 90 with the catch *h*, thus completing the coupling. The object of the spring attachment is to allow uncoupling. For this purpose the lever *H* is swung over to the opposite side of the draw-head, where it fits into a socket, *n*, and the pin *l*, attached to the chain *I* of the opposite draw-head, is passed through the hole *m* above the end of the lever, thereby confining the lever. The swinging of the lever compresses the spring *G*, thereby placing the lever under tension; and it also turns the shackle *F* one-quarter round, so that the barbs lie horizontally instead of vertically, and in this position they can draw out through the space 95 between the shoulder *g* and catch *h*, thereby un- 100

coupling the cars. In this condition, when the cars are started the first movement draws the coupling-heads out of the draw-bars, and the next movement straightens the chains I I, 5 draws the pins *l l* out of their holes, releases the levers H H, which then spring back to their original position, and turn the shackles up again in position for coupling.

If desired, a chain, *p*, may be attached to the 10 chain I, the other end being carried up and attached to the car, as shown in Fig. 6. By this means, when the pin *l* is drawn from its socket the chain I will be held up and will not fall to the ground.

15 Having thus described my invention, what I claim as new, and desire to secure by Letters Patent, is—

In a car-coupling, the combination of the shackle F, provided with a flat barbed head, the lever H, attached to the shackle, the spring 20 G, the link *k*, connecting the lever and spring, and the chain I, attached to the opposite draw-head, and provided with a pin, *l*, for securing the lever when under tension, as herein shown and described.

25 In witness whereof I have hereunto signed my name in the presence of two subscribing witnesses.

JOSEPH GEDDES.
